UNITED STATES PATENT OFFICE.

EMIL R. DRAVER, OF RICHMOND, INDIANA.

AUTOMATIC FEED-REGULATOR.

SPECIFICATION forming part of Letters Patent No. 760,435, dated May 24, 1904.

Application filed July 6, 1903. Serial No. 164,309. (No model.)

To all whom it may concern:

Be it known that I, EMIL R. DRAVER, a citizen of the United States, residing at Richmond, in the county of Wayne and State of Indiana, 5 have invented certain new and useful Improvements in Automatic Feed-Regulators; and I do hereby declare the following to be a full, clear, and exact description of the invention, such as will enable others skilled in the art to 10 which it appertains to make and use the same.

My invention relates to automatic feed-regulators of the class designed to afford a continuous feed of grain or other material which shall be constant in weight per unit of time, 15 and has for its object to provide an improved machine of this general type.

To this end my invention consists of the novel devices and combination of devices which will be hereinafter described, and defined in the claims.

The invention is illustrated in the accompanying drawings, wherein like notations refer to like parts throughout the several views. In said drawings, Figure 1 is a view of my 25 improved machine chiefly in side elevation, but with some parts broken away and others shown in section. Fig. 2 is a vertical central section through the machine on the line $x^2 x^2$ of Fig. 3. Fig. 3 is a horizontal cross-section 30 on the line $x^3 x^3$ of Fig. 2.

The numeral 1 represents a suitable casing or shell adapted to be supported above a roller-mill or other machine which is to be supplied from the feed-regulator. As shown, the casing 1 is in the form of a cylinder open at its lower end, but closed at its upper end and provided in its upper end wall or head with an inlet-thimble 2, to which the stock is supplied from a supply-chute or other source 3. 35 The casing 1 is also provided with two pairs of knife-edged fulcrums 4, fixed to the exterior walls thereof. On the said fulcrums 4 are mounted a corresponding pair of bifurcated levers, (marked, respectively, 5 and 6,) which levers are coupled together at their main or long arms by a rigid link 7. From the upper lever 6 is suspended by hanger-arms 8 a sleeve 9, which telescopes with the inlet-thimble 2 and co-operates with a fixed cone 10 to afford 45 the supply-valve for the feed-regulator. The

cone 10 is mounted point upward and is secured to the inclined walls of a fixed hopper 11, which spans the interior of the casing 1 and is made fast to the walls thereof. The cone 10 is directly above the outlet of the fixed hopper 11. 55 From the other or lower pivotal lever 5 by angular hanger-rods 12 is suspended within the casing a movable receiver or controlling-hopper 13. On the long arm of the lever 5 is adjustably mounted a counterbalancing-weight 60 14, the lever-arm being graduated to indicate divisions in weight, such as pounds. The walls of the casing 1 are suitably slotted to permit the passage of the hanger-arms 8 and 12 and the required vertical movements thereof. To 65 one of the prongs of the pivotal lever 5 is pivoted a depending rack 15, which engages with the initial member of a train of multiplying-gears 16, which, together with the small fan 17, to which said gears impart motion, are mounted within a suitable small case 18, shown as fixed to the casing or shell 1 of the feed-regulator. The top wall of the small casing 18 is slotted to pass the rack 15. The parts 16, 17, and 18 constitute an ordinary 70 75 so-called "clock-fan" or strike-wheel check used in clocks and co-operates with the pivotal rack 15 to prevent small vibrations, and thereby avoid the trembling which might otherwise interfere with the proper action of the 80 pivotal lever 5 and the parts supported and controlled thereby. A back-stop 19 holds the rack 15 in mesh with its co-operating pinion of the train 16.

Having regard now to the action of my improved feed-regulator, parts of which have been above named, it is of course obvious that the levers 5 and 6 move together and that the opening between the parts 9 and 10, which co-operate to afford the supply-valve, will be 85 varied according to the movements of the levers 5 and 6. If the outer or longer arms of the levers 5 and 6 rise, the valve-sleeve 9 will be lowered and the opening at the supply-valve be correspondingly decreased, and of course 90 if the outer or longer arms of the levers 5 and 6 lower the sleeve 9 will be raised and the opening between the parts 9 and 10 be correspondingly increased. Let it now be noted 95 that the controlling-hopper 13, carried by the 100

counterweighted lever 5, has an outlet much less than its open top or inlet and less than the intended normal feed from the supply-valve and through the machine. From this 5 fact or feature it follows that under the normal feed the controlling-hopper 13 will fill up and run over. Hence it further follows that a substantially constant bulk of continuously-changing stock will be available within the 10 controlling-hopper 13 for controlling the supply-valve according to the weight of the stock in the hopper 13, so as to maintain a continuous feed which shall be constant in weight per unit of time. The adjustable weight 14 15 may of course be set to afford any desired opening at the supply-valve made up of the coöperating parts 9 and 10, or, otherwise stated, the weight 14 may be set to give any desired normal feed for any given line of 20 stock. Thereafter the machine will become automatically adjustable to maintain the continuous feed constant in weight per unit of time, notwithstanding variations in bulk due to differences in the quality of the stock or 25 from other causes. Suppose, for example, the weight 14 has been set so as to establish a nomal feed of, say, ten pounds of grain per minute of time. The controlling-hopper 13 will not pass that much through its outlet, 30 but will fill up and overflow at the top. The outlet from the hopper 13, however, will permit the stock within the hopper to continuously change. Hence if any change should occur in the weight of the stock admitted 35 through the supply-valve the changed weight of the bulk thereof within the hopper 13 will correspondingly change the coupled levers 5 and 6, so as to vary the opening at the supply-valve to maintain the same feed of, say, 40 ten pounds per minute, notwithstanding the change in the quantity or bulk of the stock which may require to be fed. From the foregoing it must of course be obvious that the normal feed is the weight of the stock regardless of bulk, or, otherwise stated, the quantity of stock measured in weight which passes 45 through the machine in any given unit of time. This depends on the position of the adjustable weight 14, which is set once for all 50 for any given kind or class of stock in the position required to secure and insure the said normal feed per unit of time, or, in other words, the weight of that kind of stock desired to be fed through the machine in the 55 given unit of time. The normal feed for the receiver 13 from the supply-valve, made up of the parts 9 and 10, is exactly the same as the normal feed through the machine. Otherwise stated, the feed from the supply-valve and 60 the discharge from the machine are the same, as the latter depends upon the former. The control of the supply-valve, therefore, under this invention depends upon the variation in weight of a substantially uniform bulk of the 65 stock being fed. It is therefore reliable and

sensitive. This principle of action distinguishes my invention herein disclosed and claimed from any feed-regulator hitherto disclosed in the prior art designed to maintain a continuous feed constant in weight per unit 70 of time so far as the prior art is known to me. For example, the principle pointed out distinguishes my invention from the machine disclosed in the Dougan United States Patent No. 504,125, of date August 29, 1893. In 75 said Dougan machine the control of the supply-valve depends, primarily, upon the impact or striking force of the continuous stream of stock on the movable receiver. The Dougan receiver does not fill up and overflow, but 80 all the stock passes therethrough, and reliance is placed solely or primarily on the impact to effect the control. It is found in practice that the mere impact or striking force of the stream of stock cannot be relied upon to 85 maintain the desired continuous feed constant in weight per unit of time, for the reason that other things than mere weight, such as the dryness or moistness of the stock or the hardness or the softness thereof or the shape and 90 character of foreign materials commingled therewith, may change the character of the flow to such an extent as to render the impact unreliable for sufficiently sensitive control. Moreover, in regulators of the Dougan 95 type, depending primarily upon impact, the movable receiver must be located at a considerable distance from the supply-valve. This limitation does not apply to my invention. In my feed-regulator the controlling-hopper 100 may be in close contact with the supply-valve, as the impact or striking force of the stream of stock being fed is a matter of indifference.

Of course it will be understood that the supply-valve may be of any suitable construction and that the movable receiver or controlling-hopper 13 may be suspended under an adjustable counterbalance in any suitable way. It is of course equally obvious that the fixed guide-hopper 11 may be dispensed with; but 105 if used the opening through the said hopper 11 must be large enough to afford a free passage for the maximum feed from the supply-valve.

So far as the main or important feature of 115 my invention hitherto emphasized is concerned it will of course be understood that any suitable retarding device might be applied to prevent the trembling or short vibrations of the coupled levers 5 and 6 and the parts 120 supported thereby. I have found in practice, however, that a retarder made up of one or more wheels subject to some moving part of the counterbalanced receiver is more reliable and durable in practice than a dash-pot or dia-phragm such as shown or suggested in the Dougan patent. The so-called "clock-fan" or strike-wheel check herein shown is a good form of retarder; but I do not wish to be limited thereby, as one or more wheels, whether 125 130

multiplying or not, with light tension brake devices might answer equally well. It will of course be also understood that while my automatic feed-regulator herein disclosed was especially designed for use in feeding grain to roller-mills it is capable of general application for feeding many other kinds of material where the corresponding functions are desired.

What I claim as new, and desire to secure by Letters Patent of the United States, is—

1. An automatic feed-regulator, comprising a supply-valve, a counterbalanced receiver located below and arranged to continuously receive the stock from said supply-valve, said receiver having a constantly-open discharge-passage of less area than the normal area of the opening controlled by said supply-valve, and an operating connection from said receiver to said supply-valve, whereby said receiver will fill up and overflow under normal feed, thus rendering available a substantially uniform bulk of continuously-changing stock in said receiver, for controlling said supply-valve according to the weight of the stock in said receiver, to maintain a continuous feed of the stock, constant in weight per unit of time.
2. An automatic feed-regulator, comprising a supply-valve, a movable receiver located below and arranged to continuously receive the stock from said supply-valve, which receiver has a constantly-open discharge-passage of less area than the normal area of the passage controlled by said feed-valve, a variable counterbalance acting on said receiver, to fix the weight of the stock to be fed per unit of time, and an operating connection from said receiver to said feed-valve, substantially as and for the purposes set forth.
3. An automatic feed-regulator, comprising a supply-valve, a counterbalanced receiver continuously receiving from said supply-valve, an operating connection from said receiver to said valve, and a retarding device applied to prevent trembling of said receiver and coöperating parts, which retarding device is composed of a fan, a train of multiplying-gears applied thereto, and a rack or movable device, subject to a movable part of said counterbalanced receiver, and applied to the initial

pinion or member of said train of multiplying-gears, substantially as described.

4. In an automatic feed-regulator, the combination, with a supply-valve, of a counterbalanced receiver constantly receiving from said supply-valve, an operating connection from said receiver to said valve, and one or more retarding-wheels subject to a movable part of said counterbalanced receiver, or parts coöperating therewith, which retarding wheel or wheels operate to prevent the trembling or vibration of said receiver and connected parts, substantially as described.

5. The combination with a suitable casing, of a supply-valve made up of a fixed conical member 10 and a movable member 9, carried by the pivoted lever 6 and a counterbalanced receiver continuously receiving from said supply-valve and made up of the hopper 13 having a discharge of less size than the normal opening of the supply-valve, the pivoted lever 5 suspending said hopper 13 and provided with the adjustable weight 14, with the lever 5 connected by link 7 to the valve-suspending levers 6, substantially as and for the purposes set forth.

6. The combination with the casing 1, of the supply-valve made up of the fixed cone 10 and the movable member or sleeve 9 carried by the pivoted lever 6, the counterbalanced receiver composed of the hopper 13 having a discharge less than the supply thereto under the normal feed from the supply-valve, the pivoted lever 5 suspending said hopper 13, the weight 14 adjustable on said lever 5, a connection between said levers 5 and 6 for causing the same to move in unison with each other, and the retarding device comprising the rack 15 pivoted to the lever 5, the casing 18 having the fan 17, the train of gearing 16 subject to said rack 15 and the back-stop 19, for said rack, all coöperating, substantially as and for the purposes set forth.

In testimony whereof I affix my signature in presence of two witnesses.

EMIL R. DRAVER.
